SUCTION CLEANER

Charles H. Taylor, North Canton, Ohio, assignor
to The Hoover Company, North Canton, Ohio, a
corporation of Ohio

Application June 25, 1936, Serial No. 87,162

14 Claims. (Cl. 15—9)

This invention relates to improvements in suction cleaners and more particularly to improved means for converting a suction cleaner from normal on-the-floor cleaning operation to a condition for off-the-floor cleaning operations through the agency of a hose and suitable auxiliary cleaning tools.

Among the objects of the invention is to provide an improved arrangement of co-acting converter elements, consisting primarily of a converter port in the cleaner casing and a converter member or fitting carried by the hose, these elements being so related that upon the insertion of the converter fitting endwise into its port, a limited rocking movement is imparted to said fitting which in turn actuates mechanism for accomplishing automatically, the raising of the nozzle and the rotating agitator member out of contact with the carpet surface, thus avoiding undesired carpet wear.

And a further object of the invention is to improve upon a somewhat similar arrangement of interconnected converter and nozzle elevating means disclosed in Patent 2,126,362, wherein the converter element is carried on the under side of the cleaner casing and is swung by hand into and out of converting position and in its swinging movement simultaneously and automatically elevates the nozzle through a cam actuated lever 30 acting upon the forward carrier wheels. But considering the fact that most of the cleaning is performed by maneuvering the cleaner over the carpet surface, there is an advantage in transferring the converter fitting from the cleaner to the dusting tool hose, thus eliminating the added weight, but still retaining an equally practical and automatic nozzle elevating device. But in order to accomplish this end it is desirable, if not necessary, to impart an oscillating or rocking movement to the converter member for actuating the nozzle elevating mechanism, for the reason that it would take considerable physical effort to force the converter fitting into the converter port with a straight line motion and at the same time raise the nozzle from the carpet surface. Hence, it is considerably easier for the operator to insert the converter member into its port to a point just short of its ultimate position and then by a forward rocking movement to force the same home into converting position and at the same time actuate the nozzle adjusting mechanism.

Thus, while the feature of an interconnected converter and nozzle elevating mechanisms is not broadly new, the present disclosure embodies im-

proved means for accomplishing the same result with the advantages mentioned.

With the foregoing introduction to the subject matter of the present disclosure, a preferred embodiment will now be described in connection with the accompanying drawings in which,

Figure 1 is a general view in side elevation of a suction cleaner in position for normal on-the-floor cleaning operation, a portion of the cleaner casing being broken away to show details of the nozzle elevating mechanism.

Figure 2 is a bottom plan view of the cleaner with the parts in positions corresponding to those in Figure 1 and having a portion of the bottom plate broken away to show details of construction.

Figure 3 is an enlarged detail view in vertical section of the manually operated nozzle height adjusting device, showing a slip joint construction incorporated therein to permit the nozzle height adjustment to be accomplished automatically and independently of the manual adjustment.

Figure 3a is a detailed view closely associated with Figure 3 and showing the lower part of the nozzle height adjusting member in elevation.

Figure 4 is a view in side elevation of the forward portion of the cleaner casing showing the nozzle in elevated position, with portions shown in section as taken on line 4—4 of Figure 5.

Figure 5 is an enlarged bottom plan view of the cleaner corresponding generally to Figure 2 but showing the converter member parts in converted position and the carrier wheels shifted to nozzle elevated position.

Figure 6 is a detailed view in vertical section taken on line 6—6 of Figure 5 and,

Figure 7 is a detailed view in vertical section taken on section line 7—7 of Figure 5 and substantially at right angles to Figure 6.

The suction cleaner as disclosed in Figure 1 is more or less of the conventional portable or hand-maneuvered type consisting generally of a casing 1 having a nozzle portion 2 extending transversely of its forward end and presenting the rectangular conformation apparent in Figure 2. The main portion of the cleaner casing 1 constitutes the fan chamber 3, generally circular in shape and housing the fan 4 driven by a motor (not shown) located within a motor casing 5 supported upon the cleaner casing 1. The motor and fan are mounted on a vertical shaft 6, its lower end being extended below the fan to provide a pulley 7 carrying a driving belt 8 extending

ing forwardly into the nozzle portion of the cleaner casing and having a driving connection with a rotary agitator 9 journaled within the nozzle and rotating about a horizontal axis. The 5 agitator 9 has the form of a cylindrical shell provided with longitudinally arranged brush elements 9a and helically arranged beater elements 9b on the surface thereof. The mouth of the nozzle, as clearly shown in Figure 2, is formed 10 by a removable bottom plate 10 consisting of a rectangular slotted portion seating around the edges of the space occupied by the agitator and a rearwardly extending portion 10a forming the bottom wall of a converging passage from the 15 nozzle chamber to the circular opening or eye 3a leading to the fan chamber. The bottom plate 10, preferably cast from a light metal, fits tightly against the bottom edges of depending wall segments 11 which define the nozzle chamber and rearwardly extending passage therefrom, the contacting edges of said wall segments and bottom plate being suitably sealed against air leakage as clearly shown in Figures 6 and 7.

The cleaner casing 1 extends rearwardly from 25 the fan chamber 3 and terminates in a somewhat flared outlet connection 12 communicating with the fan chamber through a short connecting exhaust passage, said outlet connection 12 having detachably connected thereto a dust bag 13 by 30 means of suitable clamping screws 14.

The entire cleaner is supported upon wheels located adjacent the forward and rear ends thereof, the rear wheel support having the form of a caster consisting of a pair of wheels 15, 15 35 journaled on a caster bracket 15a attached to the under side of the cleaner casing. This rear caster is not adjustable with respect to the cleaner casing. The forward supporting wheels 16, 16 however, are journaled at the extremities of a 40 transverse rock shaft 17 having its end portion bent at right angles to form crank arms 17a, 17a. As shown in Figures 2 and 7, the shaft 17 is pivotally mounted just forwardly of the fan casing 3 in suitable brackets 18, 18, one of said brackets 45 being slightly enlarged diametrically to form a housing for a torsion spring 19 connected at one end to the shaft and at the other end suitably anchored to the cleaner casing so as to exert a tension on the shaft tending at all times to oppose any force which would rotate the shaft in a 50 counter clockwise direction as viewed in Figure 1 or Figure 4. Moreover, a bracket 20 partially embracing the shaft 17, has a circumferentially arranged slot 20a therein extending throughout 55 an arc of slightly over 90 degrees. A radially projecting lug 21 on the shaft engages within this slot and co-acts therewith to limit the rocking movement of the shaft 17 between the extreme position of the supporting wheels in elevating 60 and depressing the nozzle portion of the cleaner. And to complete the cleaner assembly, a handle 65 (not shown) is connected with the cleaner casing through the medium of an inverted U-shaped ball 22 which has pivotal connection with either side of the cleaner casing and straddles the motor casing 5.

At this point it may be stated that so much of the cleaner construction thus far described is well known and in common practice in the art, 70 including the manually operated means for adjusting the height of nozzle relative to the carpet surface. A practical device for this purpose consists of a threaded stem connected at its lower end with a pivoted or hinged front or rear wheel supporting assembly and projecting upwardly

either through the wall of the cleaner casing or a bracket and there surmounted by an adjusting screw, and which when turned in one direction or the other raises and lowers the particular wheel adjusted by oscillating the wheel support 5 in a direction to shift the wheels bodily in a vertical direction. The manual height adjusting device of the present disclosure is associated with the front wheels and is directly connected with the crank arm at one end of the shaft 17. As 10 clearly shown in Figures 1, 2, and 3, an L-shaped link 23 is connected at its lower end to the end of the crank arm 17a just inwardly from the adjacent supporting wheel 16, the upper end of said link 23 having fixed connection with the 15 lower end of threaded stem 24, forming a continuation of the link 23 and extending upwardly and rearwardly through an opening 25 in the upper wall of the nozzle portion 2 and supported adjacent its upper end in a cap-like bracket 26 20 extending over said opening 25 and having an aperture in its upper wall through which the stem projects. The outer or projecting end of the stem 24 is surmounted by a knurled thumb nut 27. Being of a standard design, this adjusting device need not be described in greater detail except to point out the two-part construction of the threaded stem 24 and the reason therefor. As clearly shown in Figures 3 and 3a, the stem 24 is tubular and encloses a solid pin 30 24a having endwise sliding connection therewith but locked against relative rotation therein by a flat face and pin connection, the flat face 24b extending lengthwise of the internal pin 24a and the pin 24c engaging said face, being carried at 35 the lower end of the tubular portion. This arrangement is simply one variation of a so-called slip joint, whereby the threaded stem 24 will shift endwise as a unit or one-piece member when the knob 27 is rotated, and at the same time be extensible to permit the wheels to be adjusted independently of the manual adjusting device as a 40 part of the converting operation.

Referring now to the novel arrangement for converting the cleaner for off-the-floor suction 45 cleaning, it may be noted at the outset that the conversion operation is primarily that of closing off the air passage from the nozzle to the fan chamber and simultaneously establishing connection between the dusting tool hose and the 50 fan chamber. In short, the act of conversion from "on-the-floor" to "off-the-floor" suction cleaning is merely a matter of by-passing the air flow to the fan chamber from the main nozzle to the dusting tool hose. In the present type 55 of cleaner, this is accomplished by inserting an especially designed converter fitting 28, secured to the one end of the dusting tool hose (not shown), into a port or passage leading inwardly from one side of the cleaner casing and communicating with the main air passage from the nozzle through a normally closed gate valve.

As clearly shown in Figures 1 and 2, the converter port or connection is formed primarily by a metal casing 29 generally U-shaped in cross 65 section and suitably attached to the under side of the cleaner casing 1. Thus, the opening or entrance to the passage formed by this casing 29, is located just below the bottom edge of the cleaner casing and immediately behind the rear 70 edge of the nozzle portion 2 on the same side of the casing as the manual nozzle height adjusting mechanism which is readily identified from the exterior of the casing by the knob 27. The converter passage from the entrance thereof in- 75

wardly is slightly convergent, that is to say, has a slight outward flare at its entrance, with the result that the opening to the converter port is considerably wider in a horizontal direction than the corresponding dimension of the fitting 28 which it is intended to accommodate, as is clearly visible in Figure 5. This flare at the entrance to the converter port is defined in part by a guide member 30 integral with the under side of the cleaner casing 1 and located at its rearmost edge, with its forward face inclined inwardly at a decided angle to the edge of the casing 1.

At the inner end of the converter passage and normally closing its entrance into the main air passage leading rearwardly from the nozzle, is a hinged gate valve 31 consisting essentially of a flat rectangular plate, elongated somewhat in a horizontal direction and fixed along its lower edge to a hinge pin 31a having its projecting ends journaled in suitable brackets 32, 32. A torsion spring 33 surrounds the pin 31a and acts to normally hold the gate valve in its closed position, that is, vertically across the opening from the converter passage into the main passage from the nozzle chamber. This opening, as clearly shown in Figure 5, is located immediately adjacent the fan eye 3a and in that portion of the wall segment 11 extending substantially tangential thereto and parallel with the normal direction of flow of the air from the nozzle to the fan chamber.

Referring in greater detail to the converter fitting 28 carried at the end of the dusting tool hose, the same has a cylindric shaped outer end portion 28a where it connects with the dusting tool hose, but immediately therebeyond it converges abruptly on all sides to form a flat sided extension 28b substantially rectangular in cross section and relatively shallow in depth, the contour of the converter member being readily apparent from Figures 5 and 6. The flattened end portion 28b of the converter fitting is perhaps 6 to 8 inches in length and quite straight with parallel edges except at its end portion 28c where one of the narrow side walls assumes a curvilinear contour which carries it substantially through 90 degrees and there meets the prolongation of the opposite side wall to form a laterally facing inlet or entrance to the converter fitting, as perhaps can best be seen in Figures 5 and 7. And further describing the contour at the outer end of the converter fitting 28, it will be noted that the length of the laterally facing inlet opening is substantially equal to the diameter of the circular fan eye 3a to the fan chamber; and again, that the somewhat irregular line denoting the bottom edge of the inlet to the converter member 28 conforms generally to a line passing diametrically through the center of the fan eye with a curvilinear recessed portion at the center thereof corresponding generally to the radius of the lower end of the fan shaft 6; and finally, that the upper wall portion of the curved end section of the converter fitting 28 has a substantially semi-circular flanged recess 28d (Figure 7) having the same radius as the fan eye 3a. Thus when the converter fitting is properly inserted, its end portion 28c extends transversely across the main air passage and completely seals or closes off the space immediately below the fan eye by contact with the inner walls of the chamber, so that the flow of air is diverted from the nozzle to the dusting tool hose through the connection made by the converter fitting 28.

In this connection, it may be pointed out that more detailed description of the exact formation

of the converter member and the method in which the conversion is performed need not be set forth in any greater particularity, inasmuch as the general type of converter member and method of sealing off the entrance to the fan chamber from the main air inlet passage from the nozzle is disclosed in an application filed on April 15, 1935, bearing Serial No. 16,381. In this earlier disclosure the converter fitting is designed to be inserted directly into the converter port without any rocking movement, an arrangement quite practical since it does not contemplate the automatic actuation of the nozzle adjusting mechanism. In the present arrangement, however, the converter fitting is initially inserted into the converter port from one angle (as shown in dotted lines in Figure 5) and then is simultaneously rocked forwardly as it is forced into its ultimate and completed position of conversion (as shown in full lines in Figure 5) to operate the nozzle elevating mechanism presently to be described.

But before doing so, the several aids for guiding and directing the converter fitting 28 into its port, will be pointed out: In the first place, there is provided along the rearmost side of the converter passage, the guide member 30, heretofore identified as marking the entrance to the passage with its inwardly projecting finger 30a and immediately beyond the end of the finger, a guide roller 34 journaled on a vertical pin 34a; and finally, a guide flange 35 extends inwardly beyond the guide roller 34 to the bearing member 32 at the inner end of passage.

Also in the bottom wall of the casing 29 forming the converter passage is an upwardly facing U-shaped groove 29a (Figure 2) slightly curved to define the center line of the passage and having a slight flare at its outer end. And cooperating with the groove 29a is a projection or lug 36 on the converter fitting 28 and projecting from the bottom side thereof, this lug 36 being so located with relation to the guide slot 29a that upon presenting the end of the converter fitting to the converter port, the lug 36 enters the guide slot 29a and thus guides the fitting inwardly in the proper path.

Now, along the rearwardly facing edge of the converter fitting is an inclined cam member, the same being formed by the wedge-shaped forward end portion 37a of an otherwise flat elongated housing 37 for a latch member for securing the converter fitting in its final position. Thus upon inserting the fitting from the angle shown in dotted lines in Figure 5, the cam member 37a first strikes the guide lip 30 and thence the guide roller 34, the latter tending to throw the fitting in a forward direction and at the same time acting as a fulcrum about which the fitting will naturally pivot as the same continues to be forced endwise into the converter passage, until it finally comes to rest in converted position as shown in full lines in Figure 5. Obviously, the gate valve 31 is swung downwardly into open position when contacted by the end of the converter fitting as shown in Figure 6.

And finally, the latching device for holding the converted fitting in its proper position, once it has been fully inserted, is shown in Figure 6. The latch member 38 is preferably in the form of a thin blade pivoted near its inner end within the housing 37 and yieldingly held in latching position by a flat spring 39. The outer end of the latch member projects upwardly through a slot in the rear portion of its casing to form a

finger-piece 38a and immediately forward of the finger-piece is an upstanding detent 38b which co-acts with the bottom edge of the side-wall of the casing 1, to hold the converter fitting in place 5 until released by depressing the finger-piece 38a.

Referring now to the mechanism for adjusting the front carrier wheels in the forward rocking movement of the converter fitting 28, there is located just forwardly of the entrance to the 10 converter port, an endwise shiftable bar 40 extending horizontally and in a fore and aft direction in alignment with the adjacent crank arm 11a of the wheel supporting shaft 11. This bar is supported intermediate its ends for sliding 15 endwise movement at the lower end of a vertical post 41 depending from the top wall of the nozzle section 2. The end of said post carries a screw 41a engaging a slot 40a extending generally lengthwise of the bar although it has a slight 20 curvature so that as the bar is shifted endwise it is at the same time shifted laterally, to maintain the sliding bar in alignment with the crank arm 11a. The forward end of the sliding bar has abutting contact with the crank arm through the 25 medium of a U-bend 40b, whereas it is pivotally connected at its rear end to the free end of a short link 42 extending substantially at right angles to the bar and laterally along the rear edge of the nozzle portion 2 of the cleaner casing. 30 This link is pivotally supported at its outer end in a fixed U-shaped bracket 43 and turns on a vertical pivot pin 43a. A torsion spring 44, coiled around the pivot pin 43a, acts upon the link 42 to swing it inwardly and rearwardly and 35 indirectly, to shift the sliding bar 40 into its normal position at the rearmost extremity of its endwise movement shown in Figure 2. At the junction of the bar 40 and the link 42 is a small roller 45 journaled at the upper end portion of the pin 45a forming the pivotal connection between these members. As clearly shown in Figures 1 and 4 this roller lies above the sliding bar 40 and in the plane of the converter fitting 28 with which it contacts when the latter is inserted into the converter port and then 40 rocked forwardly in the act of completing the converting operation. Manifestly then, the converter fitting contacting the roller 45 produces a cam action which shifts the bar 40 in a forward direction bringing its forward end in contact with the crank arm 11a of the wheel supporting shaft thereby swinging it forwardly and into a 45 substantially vertical position, as shown in Figure 4, in which position the nozzle or forward portion of the cleaner casing is elevated to its maximum distance above the carpet surface. On the other hand, upon removing the converter fitting 28 in the act of restoring the cleaner to on-the-floor operation, the weight of the cleaner 50 upon the wheels naturally causes the wheel supporting crank arms to oscillate in a counter clockwise direction and resume their normal position shown in Figure 1, this action taking place immediately upon the disengagement of the cam 55 roller 45 by the converter fitting 28.

Thus to summarize the operation of converting the cleaner from "on-the-floor" to "off-the-floor" cleaning, it is only necessary to insert the converter fitting 28, carried at the end of the adjusting tool hose, into the converter port or opening (care being taken that the lateral opening in the forward end of the fitting is facing rearwardly and toward the center of the fan eye) and then it is simply a matter of forcing the fitting into place, its forward rocking movement

being largely controlled by the several guides to the end, that the fitting performs the task of automatically actuating the nozzle height adjusting mechanism without any particular effort on the part of the operator. And, as already 5 stated, to restore the cleaner to normal "on-the-floor" operation, it is only necessary to release the latch member 38 and withdraw the converter fitting whereupon the gate valve 31 swings upwardly into closed position and the nozzle 10 returns to its normal height setting as determined by the manually actuated adjusting device controlled through the externally mounted adjusting knob 27, this action being rendered possible 15 by the slip joint connection between the adjusting device proper and its connection with the wheel supporting shaft as hereinbefore set forth.

Having set forth a preferred embodiment of the invention, I claim:

1. In a suction cleaner adapted to be converted to and from off-the-floor cleaning operation, the combination with suction producing means including a fan chamber, of a nozzle chamber, a passage leading from said nozzle chamber to said fan chamber, a converter port 25 opening into said passage from the exterior thereof and adapted to receive a converter member connected with one end of a dusting tool hose for closing off said passage, mechanism for raising the nozzle above the floor during converted 30 operation comprising a shift lever positioned adjacent said port, and means for imparting a rocking movement to said converter member during its endwise movement into converting position to thereby actuate said shift lever. 35

2. In a suction cleaner, the combination with a suction producing unit including a fan mounted within a fan chamber, a nozzle chamber and a passage leading from said nozzle to an inlet opening to said fan chamber, of a port opening 40 into said passage adjacent said inlet opening, a converter member adapted to be connected with a dusting tool hose and to be introduced endwise into said port, the latter having an outwardly flaring passage leading thereto, whereby 45 a limited rocking motion may be imparted to said converter member during its endwise movement into converting position, and an adjustable wheel supporting member including a shiftable member mounted on said cleaner and positioned 50 in the path of the rocking movement of said converter member.

3. In a suction cleaner, the combination with a suction producing unit including a fan mounted within a fan chamber, a nozzle chamber and a 55 passage leading from said nozzle chamber to an inlet opening to said fan chamber, of a valved port opening into said passage adjacent said inlet opening, a converter member at one end of a dusting tool hose and adapted to be introduced endwise into said port, the latter having an outwardly flaring entrance and guide members for directing the converter member into converting position with a limited rocking motion horizontally in one direction, an adjustable 60 wheel supporting member mounted on said cleaner, and a shiftable member positioned in the path of the rocking movement of said converter member and operatively connected with said adjustable wheel supporting member. 70

4. In a suction cleaner, the combination with a suction producing unit, a nozzle chamber leading to said suction producing unit, means for converting said cleaner for dusting tool operation, comprising a converter member attached to 75

- the end of a hose and having a portion adapted to be inserted endwise into a port opening into the space surrounding the inlet opening to said suction producing unit, means for guiding said fitting endwise into said port from a predetermined angle and thence into its converting position with an accompanying bodily rocking movement through a predetermined angle and nozzle elevating mechanism having an operating member 5 mounted in the path of said converter fitting and actuated in the rocking movement thereof.
5. In a suction cleaner, the combination with a suction producing unit and a nozzle chamber leading to said suction producing unit, of means 10 for converting said cleaner for dusting tool operation, comprising a converter member adapted to be attached to one end of a hose and having an end portion insertable endwise into a normally closed port leading into the space surrounding 15 the inlet of suction producing unit, means for directing said converter member endwise into said port from a predetermined angle and for imparting a limited rocking movement thereto during its endwise movement into converting 20 position and nozzle elevating mechanism carried by said cleaner and operative by contact with said member in its rocking movement to elevate the nozzle during the period of dusting tool 25 operation.
- 30 6. In a suction cleaner, the combination of a suction producing unit, a nozzle chamber and a passage connecting said nozzle chamber with said suction producing unit and having a valved port, a converter member connected at one end 35 with a dusting tool hose and adapted to have its free end insertable through said port to close off said nozzle chamber from said suction producing unit, cam members in the path of said converter member acting to guide the same into 40 said port with a rocking movement, nozzle height elevating mechanism mounted on said cleaner and an endwise shiftable bar having one end positioned to be operated by said converter member during its rocking movement and operatively 45 connected with said nozzle elevating mechanism.
7. In a suction cleaner, the combination of a suction producing unit, a nozzle chamber having a passage communicating with said suction producing unit through an inlet opening and having 50 a port adjacent said opening, a valve member in said port normally closing the same, a passage leading to said port and having a flared entrance opening exterior to the cleaner casing, a converter member adapted to be connected at one end to a dusting tool hose and insertable endwise through said port to close off said nozzle chamber from said suction producing unit and to establish communication therewith through said hose, guide members located in said passage for 55 directing said converter member through said port at a predetermined initial angle and for imparting a subsequent limited rocking movement thereto, and nozzle height adjusting mechanism including a spring-pressed operating member adapted to be actuated by contact with said converter member in its rocking movement to elevate said nozzle.
8. In a suction cleaner, the combination of a suction producing unit, a nozzle chamber having a passage communicating with said suction producing unit through an inlet opening and having a port adjacent said opening, a valve member in said port and normally closing the same, a passage leading to said port and having a flared entrance opening exterior to the cleaner 60
- 70
- 75
- casing, a converter member connected to one end of a dusting tool hose and adapted to be inserted into said passage and through said port to close off said nozzle chamber from said suction producing unit, co-acting guide members located in said passage and on said converter member for directing said converter member through said port at a predetermined angle and to impart a subsequent rocking movement thereto, and nozzle height adjusting mechanism mounted on said cleaner adapted to be actuated by said converter member in its rocking movement to elevate the nozzle.
9. In a suction cleaner, the combination of a suction producing unit including a fan chamber, 15 a motor driven fan mounted in said fan chamber, a nozzle having a passage communicating with said fan chamber through a fan eye, a rotary member mounted in said nozzle, a motor driven shaft extending axially through said fan eye and into said passage, means connecting said shaft with said rotary member, said passage having a port opening laterally thereto, a converter member adapted to be inserted endwise through said port and transversely of said 20 passage adjacent said fan eye, the inner end of said converter member being shaped to seat over to a portion of said fan eye and partially around said pulley shaft, and means for guiding said converter member in an arcuate path as it approaches its converting position.
10. In a suction cleaner, the combination of suction-producing means, a nozzle communicating with said suction-producing means, an externally opening port leading to said suction-producing means independently of said nozzle and adapted to have a converter member inserted endwise therethrough with a substantially straight line movement accompanied by a limited curvilinear movement to close off said nozzle 25 chamber from said fan chamber, and guide members positioned in the path of said converter member for imparting the said accompanying curvilinear movement to the latter for the purpose described.
11. In a suction cleaner, the combination of suction-producing means including a fan chamber, a nozzle chamber, a passage connecting said nozzle chamber with said fan chamber, an externally opening port leading into said passage 30 and adapted to have a converter member inserted endwise therethrough with a substantially straight line movement accompanied by a limited curvilinear movement to close off said nozzle chamber from said fan chamber, and coacting guide members on said converter member and leading toward said port for imparting the said accompanying curvilinear movement to said converter member for the purpose described.
12. In a suction cleaner, the combination of suction-producing means including a fan chamber and a motor-driven fan, a nozzle chamber having a passage leading to an inlet opening to said fan chamber, a rotary floor contacting member mounted in said nozzle chamber and driven by a belt and a pulley carried by said fan and extending through said inlet opening and into said passage, an externally opening port and adapted to have a converter member inserted endwise therethrough with its end portion traversing said passage adjacent the inlet to said fan chamber to close off the same from said nozzle chamber, said converter member being provided with a guide member adapted to contact coacting guide surfaces located along its path to im- 75

part a limited curvilinear movement to said converter member as it approaches its seat transversely of said passage for the purpose described.

13. In a suction cleaner adapted to be converted to and from off-the-floor operation, the combination of a suction-producing unit having a fan chamber and a nozzle chamber connected with said fan chamber through an air inlet passage having an externally opening port adapted 10 to have a converter member inserted endwise therethrough for closing off said passage adjacent its inlet to said fan chamber, a carpet contacting member rotatively mounted in said nozzle chamber, means for imparting a limited transverse movement to said converter member during 15 its endwise movement into converting position, and means operative by said converter member in its transverse movement to elevate the nozzle chamber portion of the cleaner sufficiently to 20 raise said carpet contacting member out of contact with the carpet during off-the-floor operation.

14. In a suction cleaner, the combination of a suction-producing unit including a fan chamber having an inlet opening, a motor-driven fan in said fan chamber, a nozzle chamber having an air passage communicating with the inlet 5 opening to said fan chamber, a rotary agitator mounted in said nozzle chamber, a motor-driven pulley extending axially through said inlet opening and into said passage, a belt extending from said pulley to said agitator through said passage, 10 the latter having an externally opening valved port adapted to have a converter member inserted therethrough and into a position transversely of said passage to close off said inlet opening from said nozzle chamber, and coacting 15 guide members on said converter member and adjacent said port and acting to guide the end portion of said converter member around said pulley as it approaches its seat transversely of said passage. 20

CHARLES H. TAYLOR.
